DESIGN FOR A DOMESTIC BUCKET

Alan McClune Woodward, Sydney, New South
Wales, Australia

Application March 5, 1943, Serial No. 109,679
In Australia August 26, 1942

Term of patent 7 years

To all whom it may concern:

Be it known that I, Alan McClune Woodward, a subject of the King of Great Britain and a resident of Sydney, in the State of New South Wales, Commonwealth of Australia, have invented a new, original, and ornamental Design for a Domestic Bucket, of which the following is a specification, reference being had to the accompanying drawing, forming a part thereof, and in which:

Fig. 1 is a perspective view of a domestic bucket from the top thereof showing my new design, and

Fig. 2 is a perspective view from the bottom thereof.

I claim:

The ornamental design for a domestic bucket, substantially as shown.

ALAN McCLUNE WOODWARD.
